DESIGN FOR A FUR STOLE

William Mitchell, New York, N. Y.

Application March 2, 1940, Serial No. 90,627

Term of patent 3½ years

To all whom it may concern:

Be it known that I, William Mitchell, a citizen of the United States of America, residing in city of New York, county of New York, and State of New York, have invented a new, original, and ornamental Design for a Fur Stole, of which the following is a specification, reference being had to the accompanying drawing, forming part thereof.

Fig. 1 is a front view of a fur stole showing my new design.

Fig. 2 is a rear view thereof.

I claim:

The ornamental design for a fur stole, substantially as shown.

WILLIAM MITCHELL.
